CONCRETE MIXER

James E. Bushnell, North Plainfield, and John P. Faber, Dunellen, N. J., assignors to Ransome Concrete Machinery Company, Plainfield, N. J., a corporation of New Jersey

Application September 13, 1932, Serial No. 632,878

8 Claims. (Cl. 83—73)

The present improvements relate in general, to concrete mixing apparatus and in particular, to means and methods for speeding up and increasing the output of a mixer unit.

5 It is common practice to specify that the ingredients of each batch of concrete, be mixed for a certain minimum length of time to insure thorough mixing. This time element naturally limits the number of batches which can be mixed 10 by one unit in a day. A primary object of the invention therefore, is to permit a greater number of batches of concrete to be mixed in a day but to mix each one for the same length of time as heretofore.

15 A further object is to provide a novel device which will permit uninterrupted mixing and discharge of batches of concrete.

Another object is to provide equipment which will be automatic in operation.

20 A further object is to provide a novel type of mixing drum, having a plurality of chambers, whereby a batch may be mixed in one chamber, while the other is being charged, whence both chambers are separately mixing whole batches.

25 Another object is to provide a dual chamber drum wherein one batch may be mixing while another batch is being discharged.

Other objects include the provision of novel methods and details of construction, apparent 30 upon reference to the accompanying specification and drawings, in which—

Figure 1 is a longitudinal section through the mixing drum illustrating one embodiment of the improvements;

35 Figure 2 is a cross section through the inner chute only;

Figure 3 is an end elevation of the discharge end of the mixer;

40 Figure 4 is a reversed side elevation of the discharge chute and operating means therefor;

Figure 5 is a side elevation of the operating means for the inner chute;

Figure 6 is a top plan view of the control unit for the skip hoist;

45 Figure 7 is a side elevation of the parts shown in Fig. 6;

Figure 8 is a front elevation of the cam disc of the control unit;

Figure 9 is a side elevation of the mixer showing diagrammatically the entire control mechanism;

Figure 10 is a view similar to Fig. 9 illustrating a modified arrangement.

Upon reference to the drawings, the rotary 50 mixing drum 1 is provided with riding rings 2

upon which the drum revolves, being supported on a set of four bearings or supporting rollers (not shown) as is common in the art. The drum is driven by a suitable power unit P, through gearing in mesh with ring gear 3 fixed 5 about the circumference of the drum.

As illustrated, the drum is provided with the usual charging inlet 4, and discharging outlet 6 while a partition 7 is disposed between the inlet and outlet for dividing same into two compartments or mixing chambers 8, 9. The aggregates to be mixed, may be admitted to chamber 8 through spout 5 either by an overhead storage bin, from a pivoted skip such as 44, or in any other convenient manner.

15 Each chamber 8 and 9 is provided with conventional mixing blades 8a and 9a, well known in the art, so that the aggregates are mixed, first in chamber 8 and, after discharge through partition 7, then in chamber 9, whence they are 20 discharged through outlet 6. The total of the mixing periods of a batch in the two chambers amounts to the interval prescribed in the specification for the particular work.

25 Communication between chambers 8 and 9 is afforded through opening 10 in partition 7, and the transfer of a batch from the first chamber into the second chamber is preferably accomplished, in the present embodiment, through the medium of chute 11, although other agencies 30 may be provided to effect the transfer, without departing from the scope of the invention. In the illustrated embodiment, a pivoted chute is provided whereby the aggregates in chamber 8 are deflected away from opening 10, preventing 35 entrance into chamber 9, so long as the chute is in full line position (Fig. 1). When moved to dotted line position, the chute causes the discharge of the materials from chamber 8 into chamber 9. Obviously a revolving or longitudinally 40 slidable chute, readily movable into corresponding positions, may be supplied in place of a tiltable chute.

45 After the mixing period in chamber 9 has lapsed, the batch may be discharged, either manually or automatically by moving chute 12 to dotted line position (Fig. 1), whence the aggregates discharge through chute 13 into any suitable receptacle. So long as the chute 12 remains in full line position, no discharge will take place.

50 A pair of beams 17, extend longitudinally through drum 1, protrude through openings 4 and 6 and may be secured to the frame work 18 of the mixer at either end thereof. If desired, these beams may stop short of the charging 55

opening of the drum and may be fastened to the charging chute 5, just inside the drum. Upon reference to Figs. 1 and 2, the chute 11 is preferably fixed to cross shaft 14 which is journalled in bearings 15 and 16 secured to beams 17. A crank 19 fixed adjacent the end of shaft 14 may be moved from full to dotted line position (Fig. 1) for correspondingly swinging chute 11.

Means for moving chute 11 are provided by link 20, pivoted to cranks 19 and 21, the latter being fixed to shaft 22, outside of the mixer drum. It is noteworthy, that the right hand beam 17 (Fig. 2) is provided with an auxiliary plate 17A, which forms a sealed, closed chamber 17B for housing the elements 19 and 20 and protecting them from the entrance of concrete, etc. Bearing 15 is also sealed against interfering materials.

Referring to Fig. 3, it is seen that shaft 22 is actuated through a series of elements 23 to 26 by a power driven mechanism 27, similar to that described and claimed for operating chutes in the patent to Shafer No. 1,415,411, issued May 9, 1922. The details of this construction are not illustrated here as they form no part of the present invention. For purposes of this description, it is sufficient to state that upon withdrawal of arm 27A from notched disc 27B (Fig. 3) the mechanism 27, driven by suitable gearing (not shown) etc. in mesh with ring gear 3, serves through the connections previously mentioned, to swing chute 11.

Referring to Fig. 3, the mounting and actuating means for chute 12 is illustrated, since certain of these elements have been omitted in Fig. 3 to avoid confusion. Chute 12 is fixed on shaft 28, journalled in bearings 29 mounted on frame 18. Shaft 28 is connected to another chute operating mechanism 34 (similar to mechanism 27 above-mentioned) by means of elements 30, 31, 32 and 33. This mechanism 34 is likewise driven from ring gear 3, upon withdrawal of arm 34A from notched disc 34B. As is well known, the withdrawal of arms 34A and 27A, permits the engagement of clutches, as will be seen upon reference to said patent.

The chute operating devices 27 and 34 may be operated by either manual or automatic (mechanical) operation of arms 27A and 34A. Through the agency of gears, clutches, etc., as described in the above mentioned patent, the chutes 11 and 12 may be swung back and forth from full to dotted line positions and vice versa, at the end of which travel they automatically stop.

Referring to Fig. 9, the loading skip 44 is seen to be of the double pivot type, having pivots at *a* and *b*, as set forth in the patent to Faber No. 1,767,443, issued June 24, 1930, although any other mounting for the skip may be employed. The skip is elevated and lowered through cable *c* and sheaves *s*, being controlled by drum 43, having a hoist clutch 43A for deriving power from power shaft 48 from unit *P*, for elevating the skip, and a brake means 43B, for lowering same.

The drum 43 is mounted on the mixer drive shaft 48, which is journalled in bearings, one of which is shown at 49 (Fig. 6). Any suitable mechanism may be employed for engaging the clutch 43A and elevating the skip 44, as is common in the art. A conventional showing in Figs. 6 and 7, is found where shaft 50 is provided for this purpose. This shaft 50 has arm 51 keyed thereto, which may be attached at 51A to a hand lever (not shown). A bracket 52 on arm 51, carries

roller 53 disposed in the path of travel of cam 65 on disc 63.

A timing mechanism 42 includes clutch member 55, slideable on a key on shaft 48 and adapted to be engaged with pinion 54, loosely mounted thereon. Clutch 55 is moved by means of trunnion ring 56, engaging yoke 57, attached to shaft 58 journalled in bearings on frame 59. As illustrated, pinion 54 meshes with a gear train 60, 61, the latter gear being keyed to shaft 62, whereby a relatively slow motion is imparted to said shaft. A disc 63, keyed to shaft 62, is provided in rim 63A, with notch 64, and with an adjustably mounted cam 65. The cam may be located at any point about the periphery of the disc (Fig. 8) so that the distance from notch 64 may be varied.

A lever 66, carrying roller 67, is releasably held by spring 68, with the roller riding on the rim 63A of disc 63. A rod 69, attached to lever 66, extends to and is connected with lever 70, keyed to shaft 58. The urge of spring 68, tends to move levers 66 and 70 in a clockwise direction, for disengaging clutch 55. A cable or rod 41 is attached to lever 66 for overcoming the spring and for pulling said levers counterclockwise (Fig. 7), for engaging clutch 55, said cable being attached to lever 37 (Figs. 5, 9).

Referring again to Fig. 9, a lever 46, operable by lug 45 on the pivoted skip frame, is connected by cable 47 to arm 27A for starting the operation of chute operating mechanism 27, for moving chute 11. A batch meter timing mechanism 71, is provided for timing the mixing interval. An actuating rod 90, is connected to the batch meter and has a free end protruding for resetting the meter 71, by skip 44, during the final portion of its movement to discharge position. A connection 91 is operated by batch meter 71, when rod 90 is actuated, for locking manual lever 100 against actuation.

Upon reference to Figs. 5 and 9, it is seen that lever 37 has cables 41 and 39 attached thereto, the latter leading to and connected with arm 34A for actuating chute operating mechanism 34, for swinging chute 12. A trip 35, fixed for rotation with shaft 22 moves lever 37 from full to dotted line position, the spring 38, returning the lever to full line position. A dog 36, pivoted on lever 37, so as to freely move to dotted line position (Fig. 5) permits trip 35 to return beyond lever 37 in a counterclockwise direction. An operator's discharge control lever 100 is also attached to cable 39 for manually actuating same. This lever 100 is locked against untimely operation by connection 91 from the batch meter 71, as aforementioned.

A foot pedal 93 with cable 94 attached to arm 27A provides for manually starting the operation of chute 11. A conventional clutch release rod 95 is actuated by the skip, for suitably releasing hoist clutch 43A when the skip approaches the end of its upward travel.

In describing the cycle of operation, it will be assumed that batches of concrete are being mixed in chambers 8 and 9. When the mixing interval, set on batch meter or timing mechanism 71, for the mixture in chamber 8, has transpired, the rod 91 is operated by the batch meter, thereby unlocking lever 100, which may now be manually operated by the operator. This withdraws arm 34A from notched disc 34B permitting power discharge mechanism 34 to swing chute 12 to dotted line, discharge position 75

(Fig. 1), thereby effecting discharge of the batch from chamber 9.

At this stage in the cycle, the operator depresses the foot pedal 93 to transfer the batch being mixed in chamber 8 to chamber 9. The time for doing this is at the option of the operator, who may actuate the pedal as soon as he observes the discharge from chamber 9 completed and sees that the truck for loading the skip is clear thereof. Actuation of pedal 93 causes inner chute 11 to move from full to dotted line (discharge) position, and the contents of chamber 8 are emptied into chamber 9. During this operation, the movement of shaft 22 causes trip 35 to rock lever 37, whereby mechanism 34 is again actuated, and outer chute 12 is swung to full line (non-discharging) position.

As lever 37 is rocked by the above described action, cable 41 is pulled thereby setting the timer 42 in motion. Upon reference to Figs. 6 and 7, it is seen that a pull on member 41 in opposition to spring 68, withdraws roller 67 from notch 64 in disc 63, and rocks lever 10, engaging clutch 55. Normally roller 67 rests in notch 64, and clutch 55 is disengaged. Power from shaft 48 (derived from unit P) causes disc 63 to revolve very slowly carrying cam 65 toward roller 53 disposed in its path. After the proper interval, predetermined by suitable location of cam 65 with respect to notch 64, roller 53 is encountered by said cam, and the roller is forced outwardly by continued rotation of the cam. As illustrated, the roller rides up in the cam 65 (Fig. 7) and shaft 50 is thereby rocked causing hoist clutch 43A to be engaged, whereby elevation of skip 44 is begun.

The clutch 43A is of the conventional self locking type and remains engaged until the skip completes its travel and moves knock-out lever 95. Obviously, continued rotation of disc 63, causes roller 53 to ride down off of cam 65, and upon completion of the 360° revolution of the disc, roller 67 again enters notch 64. Clutch 55 is thereby released and the timer 42 ceases to function.

An additional batch of dry aggregate in skip 44, is elevated and discharged into chamber 8. As described, the upward movement of the skip causes parts 45 and 46 to actuate cable 47, for again operating inner chute 11, and returning it to full line (non-discharging) position. Final upward movement of the skip actuates members 90 and 95. The former sets the mixing interval on the meter 71 and locks handle 100 against untimely operation. Member 95 releases clutch 43A thereby preventing further elevation of the skip, whereupon the automatic brake 43B holds the skip in elevated position whence it may be lowered by manually releasing the brake.

This completes the cycle of operation, which may be repeated when the batch meter 71 again releases handle 100.

Cam 65 has a steep slope on its rear face to give a quick release from roller 53 in order to permit the operator to manually disengage the skip after it has started to rise, if the necessity should arise.

Disc 63 has a series of holes through any of which cam 65 can be bolted. The distance in the direction of rotation that cam 65 is from notch 64 determines the time which elapses from the moving of chute 11 to the start of raising of the loading skip 44 and in this manner just sufficient time can be made to elapse to permit the contents of chamber 8 to be transferred to

chamber 9 before the new batch enters chamber 8. The timing mechanism 71 acts to insure the materials remaining in the mixing drum a specified length of time.

Upon reference to the modified arrangement 5 illustrated in Fig. 10, it is seen that the pedal 93 and cable 94 are dispensed with, so that the operation of chute 11 follows that of chute 12, without depending upon the operator. In this form, the batch meter or timing mechanism 71 10 is of special construction, which forms the subject matter of a separate application.

The shaft 28 (Fig. 10) is operatively connected to batch meter 71 by rod 105, while rod 106 extends downwardly to actuate power operated 15 means 107, which in turn is connected to chute 11 operating mechanism 27, and 27A by cable 108.

When operator's handle 100 has been moved, and chute 12 is actuated by mechanism 34, this 20 movement of shaft 28, through shaft 105, sets in motion another part of meter 71, and after a predetermined interval (sufficient to allow chamber 9 to be discharged), the rod 106 is actuated by the timer. This permits control device 25 107 to pull cable 108 and thereby actuate chute control means 27 whereby inner chute 11 is moved to discharge (dotted line) position, to transfer the batch in chamber 8 to chamber 9.

The remainder of the cycle is the same as that 30 described with respect to Figs. 1 to 9. It is therefore seen, in the modified form, that the operator's attendance is needed only once, viz. for pulling handle 100, whereupon, a complete cycle is accomplished without further attention. 35

In both arrangements described, it is apparent that separate batches may be mixed in the one dual drum but in separate chambers thereof so that each batch is kept separate and distinct from any other batch. Because two batches 40 are mixing at once the time between discharge of successive batches is much shorter than in the standard single compartment drum machine and the output increased to one and one-half or one and two thirds. 45

It is understood that the present invention has been described as applied to a paver unit, although it is adaptable to any type of concrete mixing apparatus.

Among other details of importance, it is noteworthy that the middle chute 11 is positioned so as to be free of the port 10, when it is in non-discharging (full line) position. This insures against accidental or inadvertent transfer of aggregate from one chamber to the other, 55 since chute 11 deflects the aggregate away from chamber 9.

Various modifications of the improvements may be made without departing from the scope and purview of the invention. 60

We claim:

1. A concrete mixing and distributing machine comprising a hollow cylindrical drum defining a mixing chamber and having a plurality of mixing compartments therein and mounted for rotation, means for rotating the same, said drum having charging and discharging openings therein, batch charging and discharging devices adjacent said openings respectively and means for operating the same to charge the drum with 65 a batch of unmixed aggregates and discharge said batch therefrom in mixed condition through said openings, mixing devices in said compartments mounted on and to rotate with said drum for mixing the said batch, a partition in the 70 75

interior of said chamber dividing the same into said plurality of compartments and having an opening therein through which the aggregates may be transferred from one compartment to the other, transferring means in said chamber including a chute-like part, said means being movable to transferring and non-transferring positions and while in non-transferring position being operative in one compartment and inoperative to either cause or, in its combination and arrangement with respect to the mixing means, permit movement of aggregates from one compartment to the other and being out of frictional contact either directly or through the aggregates with said partition.

2. A concrete mixing and distributing machine comprising a hollow cylindrical drum defining a mixing chamber and having a plurality of mixing compartments therein and mounted for rotation, means for rotating the same, said drum having charging and discharging openings therein, batch charging and discharging devices adjacent said openings respectively and means for operating the same to charge the drum with a batch of unmixed aggregates and discharge said batch therefrom in mixed condition through said openings, mixing devices in said compartments mounted on and to rotate with said drum for mixing the said batch, said mixing devices constructed and arranged to move said aggregates in two directions longitudinally and to move them radially of the chamber and extending substantially throughout the length thereof, a partition in the interior of said chamber dividing the same into said plurality of compartments and having an opening therein through which the aggregates may be transferred from one compartment to the other, transferring means in said chamber including a chute-like part, said means being adjustable to transferring and non-transferring positions within the drum and while in non-transferring positions being inoperative to either cause or, in its combination and arrangement with respect to the mixing means, permit movement of aggregates from one compartment to the other and being out of frictional contact either directly or through the aggregates with said partition.

3. A concrete mixing and distributing machine comprising a hollow cylindrical drum defining a mixing chamber and having a plurality of mixing compartments therein and mounted for rotation, means for rotating the same, said drum having charging and discharging openings therein, batch charging and discharging devices adjacent said openings respectively and means for operating the same to charge the drum with a batch of unmixed aggregates and discharge said batch therefrom in mixed condition through said openings, mixing devices in said compartments mounted on and to rotate with said drum for mixing the said batch, said mixing devices constructed and arranged to move said aggregates in two directions longitudinally and to move them radially of the chamber and extending substantially throughout the length thereof, a partition in the interior of said chamber dividing the same into said plurality of compartments and having an opening therein through which the aggregates may be transferred from one compartment to the other, transferring means in said chamber, including a chute-like part, said means comprising a concave concrete receiving and discharging member wholly within the drum movable to transferring and non-transferring positions and

while in both positions being inoperative to either cause or, in its combination and arrangement with respect to the mixing means, permit movement of aggregates from the second compartment to the other and being out of frictional contact either directly or through the aggregates with said partition.

4. A concrete mixing and distributing machine comprising a hollow cylindrical drum defining a mixing chamber and having a plurality of mixing compartments therein and mounted for rotation, means for rotating the same, said drum having charging and discharging openings therein, batch charging and discharging devices adjacent said openings respectively and means for operating the same to charge the drum with a batch of unmixed aggregates and discharge said batch therefrom in mixed condition through said openings, mixing devices in said compartments mounted on and to rotate with said drum for mixing the said batch, a partition in the interior of said chamber dividing the same into said plurality of compartments and having an opening therein through which the aggregates may be transferred from one compartment to the other, transferring means in said chamber including a chute-like part, said means being movable to transferring and non-transferring positions and while in non-transferring position being inoperative to either cause or, in its combination and arrangement with respect to the mixing means, permit movement of aggregates from one compartment to the other and being out of frictional contact either directly or through the aggregates with said partition and said transferring means being operative while in no-transferring position to direct away from said last-named opening and effect mixing movement of the aggregates.

5. A concrete mixing and distributing machine comprising a hollow cylindrical drum defining a mixing chamber and having a plurality of mixing compartments therein and mounted for rotation, means for rotating the same, said drum having charging and discharging openings therein, batch charging and discharging devices adjacent said openings respectively and means for operating the same to charge the drum with a batch of unmixed aggregates and discharge said batch therefrom in mixed condition through said openings, mixing devices in said compartments mounted on and to rotate with said drum for mixing the said batch, a partition in the interior of said chamber dividing the same into said plurality of compartments and having an opening therein through which the aggregates may be transferred from one compartment to the other, transferring means in said chamber including a chute-like part, said means being movable to transferring and non-transferring positions and while in non-transferring position being inoperative to either cause or, in its combination and arrangement with respect to the mixing means, permit movement of aggregates from one compartment to the other and being out of frictional contact either directly or through the aggregates with said partition, a fixed support for transferring means inside the drum, operating means connected therewith inside the drum and extending to the exterior of the drum and protecting means for said operating means extending over the same and between such means and the upper part of the drum.

6. A concrete mixing and distributing machine comprising a hollow cylindrical drum defining

a mixing chamber and having a plurality of mixing compartments therein and mounted for rotation, means for rotating the same, said drum having charging and discharging openings therein, batch charging and discharging devices adjacent said openings respectively and means for operating the same to charge the drum with a batch of unmixed aggregates and discharge said batch therefrom in mixed condition through said openings, mixing devices in said compartments mounted on and to rotate with said drum for causing longitudinal and angular movements of the aggregates and mixing the said batch, a partition in the interior of said chamber dividing the same into said plurality of compartments and having an opening therein through which the aggregates may be transferred from one compartment to the other, transferring means in said chamber and operating within one of said compartments including a chute-like part, said means being movable to transferring and non-transferring positions and while in non-transferring position being inoperative to either cause or in its combination and arrangement with respect to the mixing means, permit movement of aggregates from one compartment to the other and being out of frictional contact either directly or through the aggregates with said partition.

7. A concrete mixing and distributing machine comprising a hollow cylindrical drum defining a mixing chamber and having a plurality of mixing compartments therein and mounted for rotation, means for rotating the same, said drum having charging and discharging openings therein, batch charging and discharging devices adjacent said openings respectively and means for operating the same to charge the chamber with a batch of unmixed aggregates and discharge said batch therefrom in mixed condition through said openings, mixing devices in said compartments mounted on and to rotate with said drum for mixing the said batch, a partition in the interior of said chamber dividing the same into said plurality of compartments and having an opening therein through which the aggregates may be transferred from one compartment to the other, transferring means in said chamber and within one of said compartments including a chute-like part, said means being movable to transferring and non-transferring positions and while in non-transferring position being inoperative to either cause or in its combination and arrangement with respect to the mixing means, permit movement of aggregates from one com-

partment to the other and being out of frictional contact either directly or through the aggregates with said partition, said charging, discharging and transferring means being arranged for timed operation, and a batchmeter device for controlling said operation.

8. In an apparatus of the kind described, the combination with a single rotatable drum having charging and discharging openings therein, mixing devices therein and an interior dividing partition dividing said interior into compartments and having an opening communicating between the compartments formed thereby, of means for charging a batch of unmixed aggregates into the first compartment through said charging opening, means in one of said compartments out of frictional contact direct or indirect with said partition and including a concave part for automatically closing communication of aggregates between said first compartment and second compartment through the operation of and while said charging means is operating to charge said first compartment, means for automatically maintaining said closure during a period thereafter while the said batch is being partly mixed in said first compartment, means for moving said closing means between the first and second compartments to cause the partly mixed batch to be discharged from said first compartment into said second compartment through said communicating opening, automatic means for closing other communication between said second compartment and the exterior thereof while the said partly mixed batch is being discharged from the first compartment into the second compartment and for a period thereafter while the same is being mixed in the latter, means for opening the discharging opening from the second compartment and causing the batch of mixed materials to be discharged therethrough while maintaining communication between the said compartments closed, automatic means for maintaining the last named closure while the said aggregates are being mixed in the second compartment and while a new batch of unmixed aggregates is being charged into the first compartment and automatic means for carrying on said mixing operation in the second compartment and holding the aggregates therein during such charging operation and for a period thereafter, the said means being constructed and arranged to be operated successively in timed relation and continuously.

JAMES E. BUSHNELL.
JOHN P. FABER.
